UNITED STATES PATENT OFFICE.

GEORGE W. SHEPPARD, OF TORONTO, ONTARIO, CANADA, ASSIGNOR OF ONE-HALF TO
JAMES REID CAMERON, OF TORONTO, CANADA.

PRIMER.

1,147,193.

Specification of Letters Patent.

Patented July 20, 1915.

Application filed June 26, 1914. Serial No. 847,448.

To all whom it may concern:

Be it known that I, GEORGE W. SHEPPARD, a subject of the King of Great Britain, residing at Toronto, in the county of York, 5 in the Province of Ontario, Dominion of Canada, have invented new and useful Improvements in Primers, of which the following is a specification.

My invention relates to a primer and has 10 as its principal object the provision of a device which may be used for facilitating the starting of gas or explosion engines during cold weather.

A further object of my invention resides 15 in the particular combination and arrangement of parts hereinafter described.

In the accompanying drawings:—Figure 1 is a perspective view of a device embodying my invention, parts being broken away. 20 Fig. 2 is a central sectional view of the device shown in Fig. 1, but omitted from Fig. 2. Fig. 3 is a detail view in perspective of the parts shown in Fig. 1.

In the separate views the same part is designated by the same reference character.

Referring more particularly to the drawings, 1 is a hollow base or body casting on top of which is set a heavy casting 2, the casting 2 being removable at will by means 30 of an eye bolt 12. The top portion of the casting 1 has a central aperture over which is a spider such as 15 which is provided with a plurality of radial apertures such as 6 opening into the interior of the casting 2. 35 Within the casting 2 and mounted on top of the spider 15 is a reservoir 3 within which is a partition 4 of gauze wire inclosing an interior chamber, the inner chamber being covered by a removable top 5. Leading 40 from the bottom of the inner chamber just mentioned to the top of the spider 15 is a pipe 7 which passes downwardly through the casting 1 and, as shown in Fig. 1, carries at its lower end a T 13. Connected to 45 the T 13 are two cocks or taps 14 and 17, the tap 14 being connected to the gasoline supply at the carburetor while the tap 17 leads to the atmosphere.

Connected to the interior of the casting 1 50 is a short nipple 16 carried on which is an elbow 9 and contacting with the elbow 9 is a second elbow 8, the end of which removed from the elbow 9 is closed by a cap 10 which carries a plurality of nozzles 11. The nozzles 11 are intended to fit into the air inlet

of the carburetor when the engine is being cranked and the elbows 8 and 9 may be so swung that the cap 10 is entirely removed from the carburetor inlet after the engine has been started.

In using my starting device the casting 2 is removed from the casting 1 and placed in the fire while the reservoir 3 is partly filled with water. Gasoline is then admitted into the reservoir 3 by turning the tap 14 whereby gasoline is admitted to the central portion of the reservoir inclosed within the gauze 4. The cap 5 is then placed over the top of the gauze 4 and the heated casting 2 replaced as shown in Figs. 1 and 2. The engine is then cranked and at the same time the tap 17 is opened so that air is drawn through the pipe 7, the water and gasoline in the reservoir and against the sides of the casting 2. The hot carbureted air is then drawn through the casting 1, the elbows 8 and 9, the nozzles 11 and into the air inlet of the carburetor. It will be understood that water is used in the reservoir 3 in order to prevent an explosion.

Having thus described my invention, what I claim is:—

1. A device for starting gas engines comprising in combination, a heat accumulator, a fuel reservoir, means for leading air 85 through the fuel reservoir and into contact with said accumulator, and means for leading the heated carbureted air through the engine, said means comprising at least one nozzle adapted to project into the carburetor 90 inlet and a pivotally mounted elbow on which said nozzle is carried.

2. A priming device for explosion motors comprising in combination, a hollow base casting having a central aperture therein, a 95 spider mounted above said aperture, and a removable heat accumulator adapted to be placed so as to cover said spider.

3. A priming device for explosion motors comprising in combination, a hollow base 100 casting having a central aperture therein, a spider mounted above said aperture, a removable heat accumulator adapted to be placed so as to cover said spider, a fuel reservoir mounted above said spider, and 105 means for feeding air through said reservoir.

4. A priming device for explosion motors comprising in combination, a hollow base casting having a central aperture therein, a spider mounted above said aperture, a re- 110

2
movable heat accumulator adapted to be placed so as to cover said spider, a fuel reservoir mounted above said spider, means for feeding air through said reservoir, a pipe leading out from said base casting, and a pair of pivotally mounted nipples connected to said pipe.

5. A priming device for explosion motors comprising in combination, a hollow base casting having a central aperture therein, a spider mounted above said aperture, a removable heat accumulator adapted to be placed so as to cover said spider, a fuel reservoir mounted above said spider, means

for feeding air through said reservoir, a 15 pipe leading out from said base casting, a pair of pivotally mounted nipples connected to said pipe, and a cap covering the outlet of the last of said elbows, said cap being provided with a plurality of nozzles 20 adapted to project into the inlet opening of the carbureter.

In testimony whereof I affix my signature in the presence of two witnesses.

GEORGE W. SHEPPARD.
